CLAIM

The ornamental design for a sharps disposal container, as shown and described.

DESCRIPTION

FIG. 1 is a front perspective view of the sharps disposal container;

FIG. 2 is a top plan view of the sharps disposal container of FIG. 1;

FIG. 3 is a front elevation view of the sharps disposal container of FIG. 1;

FIG. 4 is a right elevation view of the sharps disposal container of FIG. 1, the left elevation view being the mirror image thereof;

FIG. 5 is a rear elevation view of the sharps disposal container of FIG. 1;

FIG. 6 is a bottom plan view of the sharps disposal container of FIG. 1; and,

FIG. 7 is a front perspective view of the sharps disposal container of FIG. 1, showing the cap in the open position. The broken line showing in the FIGS. 1 through 5 and 7 are for illustrative purposes only and forms no part of the claimed design.
